PROPELLER WITH OIL COOLER

Maurice E. Cushman, Verona, N. J., assignor to Curtiss-Wright Corporation, a corporation of Delaware

Application August 25, 1953, Serial No. 376,307

4 Claims. (Cl. 170—160.23)

This invention relates to aeronautical propellers and is particularly concerned with propeller arrangements embodying spinners and oil coolers.

As the development of large propellers for large power plants progresses, and also as improved propeller mountings on power plants are evolved, the bearings and pitch changing mechanisms of the propeller assembly absorb sufficient power so as to produce a significant temperature rise in operation. Cooling of these components may at times be accomplished most readily by cooling circulating oil used for lubricating them. In many instances, adequate cooling may be attained by routing the oil against surfaces of the propeller assembly which are kept fairly cool by their movement through the airstream in which the propeller operates. In some instances, however, it becomes necessary to provide heat transfer units in the form of coolers or radiators, whereby heat may be transferred from the lubricating oil to the airstream over a large radiating surface. When such radiation apparatus is utilized, the air which passes through the cooler and which is warmed thereby can effectively be used as a warming medium for portions of the propeller system such as the propeller spinner, which may at times require deicing.

The present invention discloses a propeller system incorporating an oil circulating system for lubrication and cooling of the propeller bearings and the pitch changing mechanism, and an oil cooler for cooling the lubricant. The cooler warms air used in lubricant cooling. A spinner arrangement is provided for the propeller, cooperating with the oil cooler in such a manner that heated air from the cooler is effectively used for spinner deicing. The invention is shown in a single embodiment and as applied to a particular propeller configuration. However, the principles of the invention are applicable to other types of propellers and to other arrangements of spinners and coolers on propellers.

Objects of the invention are: to provide a propeller bearing and pitch changing mechanism cooling system; to provide a good mechanical arrangement for an oil cooler used in conjunction with an aeronautical propeller; to provide a deicing spinner for a propeller; to combine a propeller oil cooler with a propeller spinner in such fashion that the cooler reduces the temperature of the propeller lubricant and increases the temperature of the propeller spinner.

The details of the invention may be better understood by reading the annexed description in connection with the drawing, in which the single figure is a fragmentary longitudinal section through a propeller, spinner, and cooler arrangement.

The propeller disclosed in the drawing is of a type similar to that disclosed in copending applications Serial No. 255,789 filed November 10, 1951, now abandoned, and Serial No. 375,486 filed August 20, 1953, now abandoned. The propeller includes a hub 10 having one or more blade sockets 11 in which propeller blades, not shown, are secured in known fashion for pitch change.

2

The propeller hub has journaled thereon a non-rotating pitch change mechanism encased in a housing 12, the latter being disposed on the rearward or inboard end of the propeller. The hub 10 with its associated parts is journaled on a non-rotating tubular shaft or journal member 13 for free rotation, the member 13 being secured to the nose of a power plant or reduction gear as shown in said prior applications. Bearings for supporting the propeller on the member 13 are indicated at 14 and 15. The propeller hub 10 is driven by a torque tube 16 within the shaft 13, the rearward end of the torque tube being secured to a driving member of the engine, and the forward end of the torque tube being secured to the propeller hub through a flexible coupling comprising diaphragms 17 and 18 splined at their outer edges to each other as at 19, and splined respectively to the tube 16 at 20 and to the hub 10 at 21.

The housing of the pitch changing mechanism 12 forms a sump for lubricating oil and contains an oil pump 24 driven by rotation of the propeller, the pump picking up oil from the sump and delivering it through a passage 25 to the bearing 14. The latter includes a dam 14'. The oil passes through the bearing 14 and forwardly through a conduit 26 formed by the space between the hub 10 and the shaft 13 to the forward bearings 15. Thence, the oil enters an annular cavity 27 formed by an adapter 28 disposed between the forward end of propeller hub 10 and the tube 16. The adapter includes a running seal 29 engaging a retaining nut 30, the latter engaging the shaft 13 and securing the bearings 15 in place thereon. The adapter 28 is provided with an oil transfer passage 31 leading from the cavity 27 to a port 32 in the torque tube 16. Within the torque tube is a fitting 34 having a port 35 registering with the port 32 and leading to a transfer plug 36 secured centrally in the fitting 34. Thence, oil passes forwardly through a flexible conduit 37 to a second transfer plug 36' engaging a fitting 38 having a port 39 connecting with an inlet pipe 40 of an oil cooler 41. The latter is coaxial with the propeller shaft, is disposed ahead of, and rotates with the propeller.

The cooler 41 may comprise the usual array of encased radiator tubes through which cooling air passes and around which in the intertube passages, the oil passes. Oil leaves the cooler 41 through an exit pipe 42, through an exit duct 43 in the fitting 38 to the plug 36', through a flexible conduit 44 secured to another plug 36' and thence to the fitting 34. The concentric conduits 37 and 44 define two oil passages, and these elements would normally be brazed to their end plugs 36 and 36' respectively as subassemblies. The unit 36, 37, 36' sleeves within the unit 36', 44, 36' and ports in the plugs isolate flow in one conduit from flow in the other. Exit oil passes through a port 45 in the fitting 34 to a port 46 in the torque tube 16 and thence into a port 47 in the adapter 28. The port 47 registers with the channel 48 in the propeller hub 10 which leads to part of the pitch change gearing 50 within the propeller hub. At this point, oil lubricates the bearings of gearing 50 and passes therefrom through an appropriate conduit 51 back to the sump in the pitch change mechanism housing 12. Gearing 50 includes the worm wheel and additional gearing within and carried by the propeller hub.

By the apparatus and oil path above described, it will be seen that circulating oil lubricates the main propeller bearings and the propeller pitch change mechanism, and is also passed through the oil cooler 41 to reduce the temperature of the circulating oil, the temperature having been raised by absorption of heat from the bearings and the mechanism. The oil circulating system comprises a closed circuit from the pump to the sump. Leakage of oil can be prevented by appropriate sealing devices which are disposed at appropriate locations in the

mechanism. The sealing problem is made comparatively simple since the oil circuit operates at low pressure.

As is conventional for many propellers, the propeller hub 10 is embraced by a streamlined spinner 54, the spinner having appropriate openings through which blades of the propeller project, and being supported on the propeller hub by a bulkhead 55 at its forward end, and a bulkhead 56 at its rearward end. According to the present invention, the nose of the spinner 54 is open and the material thereof is turned inwardly as at 57, 10 the oil cooler 41 being fitted to this opening. The front face of the oil cooler is thus exposed to the air-stream through which the propeller travels and air passes into and through the tubes of the cooler. Air issuing from the rear end of the cooler 41 is guided by an annular baffle arrangement comprising a cylindrical portion 58 including a closed, curved, rear end 59. This portion diverts air so that it moves forwardly around the cooler. The portion 58 joins a portion 60 at a joint 61, the portion 60 providing an inner wall for the spinner and defining with the spinner proper an annular duct 62 running along the inner wall of the spinner. The bulkheads 55 and 56 are provided with openings 63 and 64 respectively, in the passage 62, so that air from the cooler may flow rearwardly within the spinner. The air passing through the cooler 41 is warmed by contact with the radiating surfaces of the cooler so that flow of warm air through the passage 62 elevates the temperature of the spinner. This temperature rise is sufficient to prevent ice formation on the spinner under those atmospheric conditions where ice is likely to form.

The spinner 54 which rotates with the propeller comprises a forward streamlined prolongation of a non-rotating annular cowling 66. The spinner 54 is sealed relative to the cowling 66 by a seal ring 67 carried by the cowling, thus preventing the premature escape of warm air flowing through the duct 62. The cowling 66 embraces, in spaced relation, an inner cowling 69 which is also maintained in sealed relation to the spinner baffle 60 by a sealing ring 70. The cowl elements 66 and 69 are supported by a bulkhead 71, the bulkhead having openings 72 through which the warm air may pass. At some appropriate point after the bulkhead 71, the cowling 66 has openings 74 for the exit of air from the passage 62 into the free airstream or into the air intake of the power plant which drives the propeller. Should it be desirable to exhaust the air from the passage 62 somewhere along the spinner, exit openings may be provided therein, the seals 67 and 70 might be eliminated, and the bulkhead 56 could dispense with openings 64.

By the arrangement shown and described, the oil cooler 41 serves a dual purpose in reducing the temperature of the propeller circulating oil and in elevating the temperature of a quantity of air which can be utilized for deicing purposes on the spinner.

Though a single embodiment illustrating the invention is shown, it is to be understood that the invention may be applied in various forms and in various environments. Changes may be made in the arrangement shown without departing from the spirit of the invention. Reference should be had to the appended claims for definition of the limits of the invention.

What is claimed is:

1. In a tractor aircraft propeller installation, a propeller having a pitch changing mechanism including a circulating lubricant pump and a sump feeding said pump, means operated by propeller rotation to drive said pump, conduits in the propeller connected with bearings thereof fed by said pump, an oil cooler mounted on the outboard end of said propeller and rotatable therewith connected to and receiving oil from said conduits, additional conduits connected to and receiving oil from said cooler

passing through said propeller and connected to parts of the mechanism thereof, means discharging oil from said additional conduits to said sump, a spinner embracing said propeller to which said cooler is secured, the front end of said cooler passing through said spinner for exposure to the airstream, and for passage of air through said cooler, and means within said spinner to conduct air leaving the cooler, through said spinner and for discharge therefrom.

2. In a tractor aircraft propeller installation, a propeller having a pitch changing mechanism including a circulating lubricant pump and a sump feeding said pump, means operated by propeller rotation to drive said pump, conduits in the propeller connected with bearings thereof

15 fed by said pump, an oil cooler mounted on the outboard end of said propeller and rotatable therewith connected to and receiving oil from said conduits, additional conduits connected to and receiving oil from said cooler passing through said propeller and connected to parts of the mechanism thereof, means discharging oil from said additional conduits to said sump, a spinner embracing said propeller to which said cooler is secured, the front end of said cooler passing through said spinner for exposure to the airstream, and for passage of air through said cooler, and means within said spinner to conduct air leaving the cooler, through said spinner and for discharge therefrom, said latter means comprising ducting, of which the spinner forms a wall, whereby heated air from the oil cooler is effective for spinner deicing.

3. In an aircraft propeller system, a propeller including a circulating oil system for the bearings and pitch changing mechanism thereof, a fixed annular cowling aft of the propeller, a spinner for and embracing the hub of said propeller, a rearward end of said spinner blending with the forward part of said fixed cowling, an inner wall within said spinner defining therewith an air passage, an inner wall within said fixed cowling defining therewith an air passage which is a continuation of said first air passage, sealing means between the spinner and cowling, sealing means between the spinner inner wall and the cowling inner wall, said spinner at its front end having an air entrance opening communicating with said air passages, an oil cooler disposed in the spinner air passage, and oil connections between said cooler and said circulating oil system.

4. In an aircraft propeller system, a propeller including a circulating oil system for the bearings and pitch changing mechanism thereof, a fixed annular cowling aft of the propeller, a spinner for and embracing the hub of said propeller, the rearward end of said spinner

50 blending with the forward part of said fixed cowling, an inner wall within said spinner defining therewith an air passage, an inner wall within said fixed cowling defining therewith an air passage which is a continuation of said first air passage, sealing means between the spinner and cowling, sealing means between the spinner inner wall and the cowling inner wall, said spinner at its front end having an air entrance opening communicating with said air passages, an oil cooler disposed in the spinner air passage, and oil connections between said cooler and said circulating oil system, said oil connections being flexible and separable from said propeller upon removal of the cooler and spinner from said propeller.
